(57) **CLAIM**

We claim the ornamental design for a footstep for a passenger bus, as shown and described.

DESCRIPTION

FIG. 1 is a top, front, and right side perspective view of a footstep for a passenger bus according to our new design; FIG. 2 is a right side elevation view thereof; FIG. 3 is a left side elevation view thereof; FIG. 4 is a front elevation view thereof; FIG. 5 is a rear elevation view thereof; FIG. 6 is a top plan view thereof; FIG. 7 is a top and right side perspective view of a second embodiment of a footstep for a passenger bus according to our new design; FIG. 8 is a front elevation view of FIG. 7; FIG. 9 is a rear elevation view of FIG. 7; FIG. 10 is a bottom plan view of FIG. 7; FIG. 11 is a top plan view of FIG. 7; FIG. 12 is a left side elevation view of FIG. 7; FIG. 13 is a right side elevation view of FIG. 7; and, FIG. 14 is a top and front perspective view of a third embodiment of a footstep for a passenger bus according to our new design, as shown in FIGS. 1-13, showing an environment in which it might be used.

The environmental structures shown in broken lines throughout the drawings are for illustrative purposes only and form no part of the claimed design.
